(57) CLAIM

The ornamental design for a pillow, as shown and described.

DESCRIPTION

FIG. 1 is an upper perspective view of a pillow showing my new design;

FIG. 2 is a top view of the pillow shown in FIG. 1;

FIG. 3 is a bottom view of the pillow shown in FIG. 1;

FIG. 4 is a left side view of the pillow shown in FIG. 1;

FIG. 5 is a right side view of the pillow shown in FIG. 1;

FIG. 6 is a rear view of the pillow shown in FIG. 1;

FIG. 7 is a front view of the pillow shown in FIG. 1;

FIG. 8 is top view of the pillow shown in FIG. 1, illustrating another exemplary configuration of the pillow; and,

FIG. 9 is a top view of the pillow shown in FIG. 1, illustrating yet another exemplary configuration of the pillow.

The broken lines are for illustrative purposes only and form no part of the claimed design.
